ROTARY OPERATED RECIPROCATING SWITCH

John H. Horman, Tuckahoe, N. Y., assignor, by
mesne assignments, to Allied Control Company,
Inc., a corporation of New York

Application May 30, 1945, Serial No. 596,767

5 Claims. (Cl. 200—153)

1

This invention relates to relays.

An object of this invention is an improved contact mounting by means of which two sets of contacts may be brought simultaneously into engagement with the same pressure applied between co-operating pairs of contacts.

In a relay embodying this invention, a set of fixed contacts are symmetrically arranged with respect to a rotatable shaft forming part of a magnetic motor. An insulating carrier has a bore through which the shaft extends and is provided with a set of contacts complementary to the set of fixed contacts. Means are provided for preventing rotation of the carrier and the carrier bore is slightly larger than the shaft diameter so that it is capable of slight tilting relative to the shaft axis. Co-operating means are provided on the shaft and carrier for effecting movement of the carrier axially of the shaft upon rotation of the shaft. Such movement of the carrier brings its contacts into engagement with the fixed contacts and the operating pressure is distributed uniformly to the co-operating pairs of contacts irrespective of whether the plane of the fixed contacts is exactly perpendicular to the shaft axis. The carrier tilts to compensate for any deviation of the fixed contact plane from perpendicular relation to the shaft axis.

Other objects, novel features and advantages of this invention will become apparent from the following specification and accompanying drawings, wherein:

Fig. 1 is a front elevation of a relay embodying the invention;

Fig. 2 is a side elevation of Fig. 1;

Fig. 3 is a plan view of Fig. 1;

Fig. 4 is a section on the line 4—4 of Fig. 1;

Fig. 5 is a section on the line 5—5 of Fig. 6;

Fig. 6 is a view similar to Fig. 1 partially in section;

Fig. 7 is a section on the line 7—7 of Fig. 6, and

Fig. 8 is a perspective view of a part of the switch mechanism.

A magnetic metal frame 10 of U-shape is supported by a base 11 and the ends of the U legs are turned inwardly to form pole pieces 12 having concave faces 12a. A magnetic metal core 13 is supported within the frame 10 and is surrounded by a coil 14. A shaft 15 of non-magnetic metal is journaled in the core 13 and projects a considerable distance beyond the upper surfaces of the pole pieces 12. The shaft 15 has fixed thereto an armature 16 arranged in the gap between the faces 12a of the pole pieces 12 and

2

having surfaces complementary to the surfaces 12a. Springs 16a bias the armature 16 and shaft 15 counterclockwise.

A saddle 17 of non-magnetic metal is attached to the frame 10 by bolts 17a and spans the upper end of the frame 10 with an opening therethrough receiving the shaft 15 which is provided with a collar 18a underlying the saddle. An annulus 18 of insulating material rests on the saddle 17 in surrounding relation to the shaft 15 and is attached to the saddle by screws 19. A plurality of metal posts 20 are supported by the annulus 18 in parallelism with the shaft 15. The posts 20 pass through two insulating material annuli 21 and 22 with the annulus 21 being spaced from the annulus 18 by separators 23 and the annulus 22 being spaced from the annulus 21 by separators 24. Nuts 25 screwed onto the ends of the posts 20 retain the annuli and spacers in assembled relation. The annulus 21 carries three equally spaced contacts 26 and the annulus 22 also carries three uniformly spaced contacts 27 arranged in alignment with the contacts 26. Terminal members 28 and 29 are provided for the contacts 26 and 27 respectively.

A carrier 30 has a bore 31 through which the shaft 15 extends, the bore 31 being of somewhat larger diameter than the diameter of the shaft. The carrier 30 is biased toward a collar 32 on the shaft 15 by a helical spring 33 arranged between the carrier 30 and the saddle 17. A hub 34 fits over the upper end of the shaft 15 with its lower surface contacting the upper surface of the collar 32 and preferably, the bore of the hub 34 as well as that portion of the shaft 15 within the hub are of complementary shape other than circular to insure unitary rotation of the hub with the shaft. A nut 35 threaded onto the end of the shaft 15 retains the hub 34 on the shaft 15.

The hub 34 is provided with two rollers 36 having their axes arranged radially of the shaft 14 and arranged beyond the hub periphery. The carrier 30 is provided with a pair of arcuate flanges 37 coaxial with the shaft 16 and having oblique portions 38. Also, the carrier 30 is provided at its bottom surface with a plurality of contacts 39 in alignment with the contacts 26 and at its upper surface with a plurality of contacts 40 in alignment with the contacts 27. Terminals 39a and 40a are provided for the contacts 39 and 40 respectively. Notches 41 are provided in the periphery of the carrier 30 to receive the separators 24 which act to prevent rotation of the carrier 30 while permitting movement there-

of axially of the shaft 15. Rotation of the shaft 15 through an arc of less than 90° causes the rollers 36 to traverse the surfaces 38 thereby causing movement of the carrier 30 axially of the shaft 15 either against the action of the spring 33 or under the influence of said spring.

The arrangement of the armature 16 on the shaft 15 relative to the rollers 36 is such that with the coil 14 energized and the armature in the position shown in Fig. 7, the rollers 36 engage high points of the surfaces 38 so that the carrier 30 is drawn toward the annulus 21 to bring the contacts 39 into engagement with the contacts 26. Upon de-energization of the coil 14, the spring 23 lifts the carrier 30 toward the annulus 22 to bring the contacts 40 into engagement with the contacts 27 and the shaft 15 and armature 16 are rotated counterclockwise from the position shown in Fig. 7 by movement of the rollers 36 to low points on the surfaces 38 and by the springs 16a. Upward movement of the shaft 15 is prevented by the collar 15a on the shaft engaging the saddle 17.

Firm engagement of either set of three contacts of the carrier 30 with the contacts of either annulus 21 or 22 is insured by the arrangement above described. In the event that either the contacts 26 or 21 do not lie in a plane perpendicular to the shaft 15, the carrier is capable of sufficient tilt on the shaft to effect engagement of all three pairs of contacts with the same pressure applied to each pair.

It is of course understood that various modifications may be made in the structure above described without in any way departing from the spirit of the invention as defined in the appended claims.

I claim:

1. A device of the character described comprising a rotatable shaft, a pair of radial studs carried by said shaft, a carrier having a bore through which said shaft extends, means preventing rotation of said carrier while permitting movement of said carrier axially of said shaft, a pair of arcuate inclined surfaces on said carrier engaging said studs, means biasing said carrier toward said studs, a first set of contacts mounted on said carrier, and a second set of contacts supported in fixed relation for engagement by said carrier contacts.

2. A device of the character described comprising a rotatable shaft, a carrier having a bore through which said shaft extends, means pre-

venting rotation of said carrier while permitting movement of said carrier axially of said shaft, means for effecting axial movement of said carrier upon rotation of said shaft, a first set of contacts mounted on said carrier, a second set of contacts supported in fixed position for engagement by said carrier contacts.

3. A device of the character described comprising a rotatable shaft, a pair of radial studs carried by said shaft, a plurality of posts parallel to said shaft, a carrier having a bore receiving said shaft and notches receiving said posts, a pair of arcuate inclined surfaces on said carrier engaging said studs, means biasing said carrier surfaces toward said studs, a first set of contacts mounted on said carrier, and a second set of contacts supported in fixed relation for engagement by said carrier contacts.

4. A device of the character described comprising a rotatable shaft, a plurality of posts parallel to said shaft, a carrier having a bore receiving said shaft and notches receiving said posts, means for effecting axial movement of said carrier upon rotation of said shaft, a first set of contacts mounted on said carrier, a second set of contacts supported in fixed position for engagement by said carrier contacts.

5. A device of the character described comprising a rotatable shaft, a plurality of posts parallel to said shaft, a carrier having a bore through which said shaft extends and notches receiving said posts, a first set of contacts supported by said carrier, a second set of contacts supported in fixed position for engagement by said carrier contacts, co-operating means on said carrier and said shaft for effecting movement of said carrier to engage its contacts with said fixed contacts upon rotation of said shaft, and resilient means biasing said carrier in a direction to disengage said carrier contacts from said fixed contacts.
